WRIST ATTACHABLE PEN AND PENCIL HOLDER

Rundlette K. Palmer, P.O. Box 69, Newcastle, Maine

Filed Sept. 7, 1965, Ser. No. 86,885

Term of patent 14 years

(Cl. D74—21)

FIGURE 1 is a perspective view of a wrist attachable pen and pencil holder embodying my new design;

FIGURE 2 is a top plan view thereof;

FIGURE 3 is a front end view thereof, the dotted line showing of the wrist band being for illustrative purposes only; and

FIGURE 4 is a rear end view thereof, the dotted line illustration of the wrist band having been omitted for convenience of illustration.

I claim:

The ornamental design for a wrist attachable pen and pencil holder, as shown and described.
